UNITED STATES PATENT OFFICE

FRED A. SHENKER AND ISADORE WEISSBERG, OF EAST CLEVELAND, OHIO

DESIGN FOR AN AMUSEMENT DEVICE

Application filed August 11, 1931. Serial No. 40,829. Term of patent 3½ years.

To all whom it may concern:

Be it known that we, FRED A. SHENKER and ISADORE WEISSBERG, citizens of the United States, residing at E. Cleveland, in the county of Cuyahoga and State of Ohio, have invented a new, original, and ornamental Design for an Amusement Device, of which the following is a specification, reference being had to the accompanying drawings, forming part thereof.

We claim:—

The ornamental design for an amusement device as shown.

FRED A. SHENKER.
ISADORE WEISSBERG.
